GOLF BALL DRIVING DEVICE

William A. Malkan, Oakwood Heights, N. Y.

Application May 8, 1945, Serial No. 592,697

2 Claims. (Cl. 273—129)

1

This invention is for a golf ball driving device and the same has particular reference to an improved device of said character which is so constructed and arranged as to obtain relatively great striking force against the ball by downward movement by the operator of a reciprocatory plunger.

The invention has in view a golf ball driving device which may be gripped by the operator with one hand while utilizing the other hand for manipulating the plunger for effecting a driving of the ball and which device is adjustable for varying the height of the ball with the same striking force.

The invention further comprehends a spring arm having a bifurcated free end which is formed with a ball receiving depression for supporting the ball and directing the same so that accuracy may be obtained in the direction in which the ball will travel.

More particularly, the invention embodies a swinging mounted arm geared to the reciprocatory plunger and having a driving head at the free end thereof for striking a golf ball disposed in the depression in the supporting arm, the latter being adjustable for varying the direction of travel of the ball. With the foregoing and other objects in view reference is now made to the following specification and accompanying drawings in which is illustrated the preferred embodiment of the invention.

In the drawings:

Fig. 1 is a view in elevation of a golf ball driving device constructed in accordance with the invention and showing in broken lines the parts located within the device.

Fig. 2 is a vertical sectional view taken on line 2—2 of Fig. 1 with the lower portion of the device shown in elevation.

Fig. 3 is a transverse sectional view taken on line 3—3 of Fig. 2.

Fig. 4 is a transverse sectional view taken on line 4—4 of Fig. 2.

Referring to the drawings by characters of reference, the golf ball driving device includes a supporting structure or housing consisting of upper and lower tubular sections 10 and 11 arranged in vertical alignment and disposed above and below an intermediate section or casing 13 having parallel top and bottom walls 14 and 15 to which the upper and lower sections 10 and 11 are secured by studs 16 extending through the flanged ends thereof. The intermediate section or casing 13 is of rectangular shape in cross-section and is formed with aligned apertures 17

2

in the top and bottom walls 14 and 15 which open into the upper and lower tubular sections 10 and 11 respectively.

The supporting structure or housing also includes a base 18 secured to the lower section 11 by studs 19 extending through the flanged lower end thereof and which base is of a size to form a support for the structure or housing. The upper section 10 is provided with a handle member 20 having a shank 21 which is secured in the open upper end of said section by a screw 22 or other equivalent fastening means with the free end of the handle 20 extending horizontally outward to provide a convenient means for steadyng the supporting structure or housing by the operator grasping the same with one hand.

Located within the supporting structure or housing is a plunger 23 which snugly and slidably fits within the upper and lower sections 10 and 11 and extends through the intermediate section or casing 13 for reciprocatory movement longitudinally of said supporting structure or housing.

The plunger 23 is provided with a bar 24 having a cylindrical lower end portion threadedly secured in the upper end of said plunger and above said cylindrical portion the said bar is flattened and protrudes upwardly through a guide slot 25 in the handle member 20 with the extreme upper end of the bar bent at a right angle thereto to provide a handle 26 disposed in angular relation with the handle 20 and adapted to be manipulated by the other hand of the operator for imparting reciprocatory movement to the plunger 23.

In order to provide means for imparting swinging movement to an arm 27 having a driving head 28 at the free end thereof for striking and driving a golf ball, the plunger 23 is provided with a longitudinally extending rack 29 secured in a recess 30 therein by screws 31 or other fastening means to dispose the outer faces of the teeth substantially flush with the adjacent periphery of the plunger. The rack 29 is arranged in engagement with a gear 32 affixed to a shaft 33 journaled in bearing bosses 34 formed on the opposite side walls of the intermediate section or casing 13. The inner end of the arm 27 is secured by studs 35 to the outer end of the shaft 33 which protrudes through an opening in the side wall 36 of the intermediate section or casing 13.

Secured to the base 18 in offset relation thereto is a golf ball supporting member 37 having a bifurcated forward end and a ball receiving de-

pression 38 in the upper face thereof for supporting a golf ball in the path of travel of the striking head 28 of the arm 27, the longitudinal edges 39 formed by the furcations and extending forwardly from the depression 38 functioning to guide and accurately direct the ball after it is hit by the driving head 28. The golf ball supporting member 37 is secured to the forward end of a leaf spring 40 the opposite end of which is adjustably secured to a laterally extending bar 41 by means of a wing nut 42, the bar 41 being adjustably secured to the base 18 by a wing nut 43.

Constructed in this manner the golf ball supporting member 37 may be disposed in angular relation to the base 18 and to the path of travel of the driving head 28 so that when the ball is struck by the driving head the longitudinal edges 39 function to direct the ball in a direction corresponding to the angular setting of the supporting member 37. In addition to adjusting the setting of said supporting member by clamping the bar 41 and the supporting member 37 in various angular relations by means of the wing nuts 42 and 43, the driving head 28 is connected with the arm 27 for disposing either of the faces 44 or 45 forwardly for striking engagement with the ball, the striking face 45 being at an angle which will effect a greater elevation of the ball than the striking face 44. For this purpose the striking head 28 is pivotally mounted on bolt 46 which protrudes through an opening in the arm 27 and is adapted to be secured thereto by a wing nut 47. The forward ends of the furcations of the supporting member 37 are beveled as at 48 to provide means whereby the striking head 28 will pass over the end of the supporting member 37 on its return swing by camming the said supporting member downwardly should the head be turned so as to engage the said beveled edges, the leaf spring 40 resiliently mounting the supporting member 37 for such purpose.

In use and operation the operator is positioned at the rear of the supporting structure with the right foot disposed upon the rear of the base 18 for assisting in steadyng the device while the left hand of the operator grasps the handle 20 for holding the supporting structure in an upright position the operator first having adjusted the supporting member 37 in the direction that the ball is to travel, and having arranged the striking head 28 as desired. The operator then grasps the handle 26 with his right hand and forces the plunger 23 quickly downward to effect a rapid downward swinging of the arm 27 so that the head 28 strikes the ball supported in the depression 38 as indicated in Fig. 1 of the drawing and drives the same forwardly therefrom.

What is claimed is:

1. In a golf ball driving device, a supporting structure, a handle carried by said supporting structure at the upper end thereof and projecting laterally therefrom, a plunger guidedly mounted in said supporting structure for reciprocatory movement and provided with an outwardly extending handle for imparting movement to said plunger, an arm located exteriorly of said supporting structure and mounted thereon for swinging movement, said arm having a driving head at the free end thereof, a golf ball supporting member, a leaf spring connecting said golf ball supporting member with said supporting structure for supporting a golf ball in the path of travel of said driving head and forwardly of said supporting structure and means carried by said plunger and said arm for effecting swinging movement of the arm upon reciprocatory movement of the plunger.
2. In a golf ball driving device, a supporting structure, a handle carried by said supporting structure at the upper end thereof and projecting laterally therefrom, a plunger guidedly mounted in said supporting structure for reciprocatory movement and provided with an outwardly extending handle for imparting movement to said plunger, an arm located exteriorly of said supporting structure and mounted thereon for swinging movement, said arm having a driving head at the free end thereof, a golf ball supporting member, resilient means connecting said golf ball supporting member with said supporting structure at the base thereof and extending forwardly thereof for supporting a golf ball in the path of travel of said driving head and forwardly of said supporting structure and means carried by said plunger and said arm for effecting swinging movement of the arm upon reciprocatory movement of the plunger.

WILLIAM A. MALKAN.
